DISPENSING RACK FOR TUBULAR CONTAINERS

Albert C. Engelmann, 81 Irving Ave., Providence 6, R.I.

Filed Dec. 8, 1961, Ser. No. 67,841

Term of patent 14 years

(Cl. D52—2)

FIG. 1 is a front perspective view of a dispensing rack for tubular containers, showing my new design, the rear being substantially flat and plain;

FIG. 2 is a side elevation thereof;

FIG. 3 is a bottom plan view thereof; and

FIG. 4 is a sectional view taken on line 4—4 of FIG. 3.
I claim:

The ornamental design for a dispensing rack for tubular containers, substantially as shown and described.
